UNITED STATES PATENT OFFICE

CHESTER W. RICE, OF SCHENECTADY, NEW YORK, AND EDWARD W. KELLOGG, OF MOORESTOWN, NEW JERSEY, ASSIGNORS TO GENERAL ELECTRIC COMPANY, A CORPORATION OF NEW YORK

SOUND REPRODUCING APPARATUS

Application filed August 21, 1931. Serial No. 558,598.

Our present invention relates to apparatus for producing sound from electric currents corresponding to original sounds, and more particularly to devices now commonly known 5 as loud speakers.

One of the objects of our invention is to provide a device of the class mentioned whereby the reproduction of sounds may be made with greater accuracy and fidelity than 10 with devices of this class previously employed.

A further object of our invention is to provide an apparatus in which the usual horn may be dispensed with and the sound projected from the device in a more satisfactory 15 manner than with the usual form of horn.

Our present application is a continuation in part of our application Serial No. 1482, filed in the United States Patent Office January 23, 1925.

The novel features which we believe to be characteristic of our invention are set forth with particularity in the appended claims. Our invention itself, however, both as to its 25 organization and method of operation will best be understood by reference to the following description taken in connection with the accompanying drawing in which the single figure is a view partly in cross-section 30 of a device constructed in accordance with our invention.

We have indicated in the drawing a sound reproducing device comprising a diaphragm of conical form which, in the device illustrated, is specifically a truncated cone. This diaphragm in the form shown is made up of two parts. The inner member 1, which may be of thin light metal, such as aluminum, and an outer member 2 of light, fibrous material, 35 such for example, as paper, which is secured to the inner member 1, by suitable adhesive, or otherwise, as desired. By reason of its conical form the diaphragm may be light and at the same time rigid enough so that it 40 will be capable of vibrating substantially as a whole. A cylindrical member 3, which is secured to the top of the inner member 1, carries an actuating coil 4, to which the current 45 for operating the loud speaker, may be supplied. The coil 4 is disposed in the annular 50

air gap 5, which is formed between the concentric pole pieces 6 and 7. The inner pole piece 7 is surrounded by a coil 8, through which a steady direct current may be supplied for producing a strong magnetic field in the 55 annular air gap 5. The outer end or base of the diaphragm is supported by means of stretched strings 9, or by other suitable means in an opening 10 of a baffle member 11. The strings 9 permit freedom of movement of 60 the diaphragm in the longitudinal direction, but prevent movement in a lateral direction whereby the edges might strike against the wall of the opening 10. When variable currents are supplied to the coil 4, the diaphragm 65 will be caused to vibrate substantially as a whole in accordance with the variations in current supplied to the coil. Because of the flexible nature of the supporting strings 9 there may be a tendency of lateral movement 70 in the coil 4 in the air gap 5. To avoid this there is provided a ring of flexible material, for example, such as rubber or thin leather 75 12, which is secured to the base of the inner member 1, and extends outwardly therefrom to a supporting ring 13. This flexible ring 12 also permits freedom of longitudinal movement of the diaphragm, and the strings 9 and the ring 12, together constitute an effective means for preventing lateral movement 80 of any part of the diaphragm.

The restoring force of the diaphragm mounted in the way illustrated may be made so low that the natural rate of vibration as 85 a whole will be below the lowest important voice frequency. It is possible to construct such a device in a way that its natural rate of vibration as a whole will be about fifty cycles. Fairly good results however may be obtained with diaphragms having higher 90 natural frequencies of vibration even up to 200 cycles, particularly if provision is made for damping so that the resonance is not sharp. This low natural frequency is an essential feature in the construction of loud 95 speakers, in order that the diaphragm shall respond equally to all frequencies which it is desired to reproduce.

The air gap between the poles 6 and 7 must 100 be small in order to secure the best efficiency.

It will be observed therefore that the space between the inner member 1 and the inner pole 7 will be almost completely closed. Suitable venting of this space may be furnished by 5 means of the holes 14 in the ring 3. The centering ring 15, which is provided for maintaining the proper spaced relation between the poles 6 and 7, may also be cut away, as indicated at 16, to permit air to more readily 10 circulate between the ring 3 and pole piece 7. With the arrangement as thus far described, air can circulate between the front and back of the diaphragm around the supporting member 11 without undergoing any appreciable compression. This would result in substantial loss of the low tones. If, however, the path between the front and back of the diaphragm is increased to a distance of about 15 one-fourth of a wave length or more, this circulation will be substantially prevented and good radiation will be secured. This effect may be made by making the supporting member 11 of fairly massive or rigid material and making it large enough to effectively prevent 20 such circulation. This baffle effect may conveniently be obtained by inclosing the diaphragm and its actuating mechanism in a cabinet of suitable form. Preferably the back of this cabinet should be open or vented to 25 prevent any resonance effect due to confined air space within the cabinet.

While it may be shown theoretically that a small diaphragm, of such rigid construction that all parts have equal motion even at the 30 highest frequencies, and so supported that its natural frequency of vibration as a whole is below the lowest frequency to be radiated, constitutes an ideal sound reproducer, as explained in Patent 1,795,214, issued to Edward 35 W. Kellogg, on March 3, 1931, we have not found it necessary in practice to adhere to diaphragms of such small size as would be needed to comply with the condition just mentioned. For example, we have made a calculation which indicates that a paper cone, 40 four inches in diameter at the base, free at the outer edges and with an angle of 45° between axis and element will probably begin to depart materially from true plunger action at a 45 frequency between 3000 and 4000 vibrations per second. Cones with larger diameters or with larger angles between element and axis will begin to show appreciable phase and 50 amplitude differences between the different parts of their surfaces at lower frequencies. We have nevertheless obtained good results with cones up to 8 and even 20 inches in diameter and with angles as great as 64°, provided that in all cases the outer edge of the 55 cone is so flexibly supported that at low frequencies the cone moves as a whole. The probable explanation of our experience is that at the higher frequencies the diaphragm radiates sound by virtue of a progressive deflection. When a force is applied at the small 60

end of the frustum, a circular flexural wave travels out toward the outer edge, and gives off sound waves in the air as it progresses. The progressive deflection we shall refer to as "wave action" in the diaphragm while the 65 type of motion in which all parts of the surfaces have the same motion may be described as piston or "plunger action". In the devices built in accordance with our invention, true plunger action takes place at the lower frequencies and wave action presumably takes place at the higher frequencies. The transition is not abrupt, nor is it marked by any great change in radiation characteristic or efficiency which would upset the balance between the high and low frequency components or impair the general quality of sound reproduction. Within the frequency range characterized by wave action in the diaphragm 70 slight resonance may occur, for the reason that reflection of the waves takes place at the outer edge of the diaphragm. The fact that resonances do not appear to be as sharp or as strong as to impair sound reproduction is probably due to the high attenuation of 75 the waves at high frequency by energy absorption in the material of the diaphragm, and also in part to energy absorption in the flexible supports of the diaphragm.

As compared with diaphragms so small 80 that we can be sure that they act as plungers throughout the entire essential frequency range, we find a gain in sensitivity from the use of somewhat larger sizes, our best results having been obtained with diameters between 85 four and eight inches and angles between element and axis, from 45° to 70°. Diaphragms of large diameter work best with the larger angles. In the case of sound reproducing devices employing conical diaphragms, either 90 rigidly supported at the outer edge, or with a support whose stiffness in the axial direction is comparable with the stiffness of the diaphragm itself, plunger action cannot take place at any frequency. If a vibratory force 95 is applied at or near the vertex the resulting motion is greatest where the force is applied and becomes less as the edge is approached if the frequency is below the fundamental resonance. As the frequency is raised 100 a series of resonances occurs. At certain frequencies the motion is greatest at the point of application of the driving force, and at other frequencies the motion is greatest at 105 points between the vertex and outer edge. Flexural waves originating at the driving point, travel to the outer edge where they are reflected and produce standing waves with 110 circular nodes and loops of motion. At low frequencies the resonances are far apart on the musical scale, and owing to the small absorption of energy, resonance is sharp. Both 115 of these facts mean serious distortion in the reproduction of sounds. At higher frequencies the resonances are closer together on the 120

musical scale, and are less sharp because of greater relative energy absorption in the material of the diaphragm and sound radiation is therefore more nearly uniform. With a diaphragm stiffly supported at the edge, there is little motion and little sound radiation at frequencies below the first resonance. Therefore, to secure anywhere near adequate radiation of low tones it is necessary to make the diameter large and the angle between element and axis large (giving a shallow cone). Our tests indicate, however, that cones which are very shallow in comparison with their diameters fail to give adequate radiation of the very high frequency tones.

A device employing a flexibly supported conical diaphragm has the following advantages over previous devices having rigid or stiff support around the outer edge. The radiation of the low tones is much more nearly uniform and free from resonance, and the radiation of high frequencies is more satisfactory for the reason that we have more latitude in the choice of cone angle and can choose that which gives the most nearly uniform radiation of the high frequencies. Devices with stiffly supported outer edges must employ an angle which is a compromise between what is best for the high and low frequencies and is therefore not the best angle for either one. Our device has the further advantage that with plunger diaphragm action we can obtain adequate radiation of low tones with a smaller diaphragm, provided that we use a baffle in connection with the diaphragm. This means that the diaphragm is easier to protect from injury and the resulting device becomes more compact.

While in the drawing we have shown a diaphragm which is made up of two members, similar results may be obtained with diaphragms constructed of a single member of paper or other similar light material, with the inner member omitted and the actuating coil secured directly to the top of the diaphragm. It also will be evident that numerous modifications may be made in the manner in which the diaphragm is supported without departing from the scope of our invention as set forth in the appended claims.

What we claim as new and desire to secure by Letters Patent of the United States, is:

1. In an apparatus for sound reproduction, a diaphragm having the form of a truncated cone which is so rigid in comparison with its size and weight that when a driving force is applied thereto at its top all parts thereof will have substantially equal movement, means for suspending said diaphragm having so low a restoring force that its natural rate of vibration as a whole will be below the lowest important voice frequency, means for actuating said diaphragm comprising a pair of concentric pole pieces separated by an annular air gap, an actuating coil secured to the

top of said diaphragm and located in said air gap, and means in addition to the suspending means for preventing lateral movement of said coil in said air gap.

2. In an apparatus for sound reproduction, a rigid diaphragm having the form of a truncated cone, the base of said diaphragm being so flexibly supported that the diaphragm is capable of vibrating as a whole, means for actuating said diaphragm comprising a pair of concentric pole pieces separated by an annular air gap, an actuating coil secured to the top of said diaphragm and located in said air gap, and means in addition to the suspending means for preventing lateral movement of said coil in said air gap. 70

3. In an apparatus for sound reproduction, a diaphragm of conical form having a diameter between four and eight inches, the angle between an element and the axis of said diaphragm being of a value between 45° and 70°, and actuating means for producing a vibration thereof, said diaphragm being so suspended and actuated that the restoring force applied thereto will be so low that its natural rate of vibration as a whole will be below the lowest important voice frequency. 85

4. In an apparatus for sound reproduction, a diaphragm of conical form having a diameter between four and eight inches, the angle between an element and the axis of said diaphragm being of a value between 45° and 70°, an actuating means for producing a vibration thereof, said diaphragm being so suspended and actuated that the restoring force applied thereto will be so low that its natural rate of vibration as a whole will be below 200 cycles. 90

5. In an apparatus for sound reproduction, a diaphragm of conical form having a diameter between four and eight inches, and which is so supported that it is capable of vibrating as a whole, the angle between an element and the axis of said diaphragm being of a value between 45° and 70°, and means for applying a driving force to the top of said diaphragm, the restoring force applied to said diaphragm being so low that its natural rate of vibration as a whole will be below the lowest important voice frequency. 105

6. In an apparatus for sound reproduction, a diaphragm of conical form having a diameter between four and eight inches, and which is so supported that it is capable of vibrating substantially as a whole, the angle between an element and the axis of said diaphragm being of a value between 45° and 70°, and means for applying a driving force to the top of said diaphragm, the restoring force applied to said diaphragm being so low that its natural rate of vibration as a whole will be below 200 cycles. 110

7. In an apparatus for sound reproduction, a diaphragm having the form of a truncated cone which is closed at the top and which is 120

125

130

made up of an inner member of metal and an outer member of fibrous material, means for actuating said diaphragm comprising a pair of concentric pole pieces separated by an 5 annular air gap, an actuating coil secured to the top of said inner member and located in said air gap, means attached to the outer member for supporting said diaphragm so flexibly that it is capable of vibrating sub- 10 stantially as a whole, and means attached to the inner member for preventing lateral movement of the actuating coil in said air gap.

8. In an apparatus for sound reproduction, 15 a diaphragm having the form of a truncated cone which is made up of an inner member of metal and an outer member of fibrous material, means for actuating said diaphragm comprising a pair of concentric pole pieces 20 separated by an annular air gap, an actuating coil secured to the top of said inner member and located in said air gap, means attached to the base of the outer member of said dia- 25 phragm for flexibly supporting it so that it is free to vibrate substantially as a whole, and means extending outwardly from the base of the inner member for preventing lateral movement of the actuating coil in the air gap.

In witness whereof we have hereto set our 30 hands.

CHESTER W. RICE.
EDWARD W. KELLOGG.
